CLAIM

The ornamental design for a tool storage cabinet, as shown and described.

DESCRIPTION

FIG. 1 is a front, top, and right perspective view of a tool storage cabinet showing my new design;

FIG. 2 is a rear, bottom, and left perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a front, top, and right perspective view of the tool storage cabinet in an open configuration.

The broken lines shown in the drawings depict portions of the tool storage cabinet that form no part of the claimed design.
